UNITED STATES PATENT OFFICE

CLARENCE W. EHLERS, OF JUNCTION CITY, KANSAS

FARM GATE

Application filed June 8, 1928. Serial No. 283,942.

The present invention relates to gates and has for its principal object to provide a vehicle operating means therefor, whereby to open or close the gate upon the approach of a vehicle.

A still further object of the invention is to construct the gate of a pair of gate sections, with each of said sections arranged for vertical swinging movement.

Another object of the invention is to provide a vehicle operating means for each of the gate sections disposed remotely therefrom.

An additional object is to provide operating means for the sections of the gate disposed in advance of each side of the gate, and adapted for moving the sections into an open or closed position, depending upon the direction of travel of the vehicle.

Another object is to provide an apparatus of this character of a simple and practical construction, which is strong and durable, efficient and reliable in performance, relatively inexpensive to manufacture and assemble in operative position, and otherwise well adapted to the purpose for which the same is intended.

Other objects of the invention will become apparent as the nature of the invention proceeds and when taken in connection with the accompanying drawings.

In the drawing:

Figure 1 is a perspective view, showing the apparatus in assembled position.

Figure 2 is a side elevational view of one of the gate sections and the pivotal mounting therefor.

Figure 3 is a perspective view of one of the supporting posts, illustrating the operative connection of the pivotal operating means with the rock shaft provided for operation upon the passing of a vehicle thereover.

Figure 4 is a perspective view of one of the gate sections, and

Figure 5 is a similar view of the gate latch retaining staple provided for securing the gate sections in closed position.

Referring now to the drawings in detail, wherein for the purpose of illustration I

have disclosed a preferred embodiment of my invention, the numeral 5 designates a pair of uprights spaced apart gate posts, a pair of said posts being disposed at each side of the gate, each of said posts at their inner lower edges being provided with a bracket 6 for supporting the ends of a shaft 7, extending between each pair of the posts and formed at the outer lower corner of a gate section 8.

The gate sections may be constructed in any manner well known in the art, such as for instance, a rectangular shaped frame 8, having a wire mesh 9 attached to the members of said frame. If desired, the shaft 7 may be hinged, together with the frame of the gate section or may be formed separately and attached in any suitable manner to the lower outer edge of the frame as indicated in Figure 4 of the drawings. Braces 10 may also be provided for the opposite ends of the shaft and connected to the bottom frame member of the gate and rear vertical frame members to prevent bending of the shaft.

The two sections of the gate are formed in duplicate and cooperate to close the entrance therebetween, the respective sections being mounted on the gate posts. By reason of the horizontally disposed shaft 7, extending transversely at the rear edges of the gate sections, the sections are thus adapted to swing vertically between the posts 5 and at each side of the entrance. At the inner adjacent edges of the gate section is arranged a latch 11, secured at one end of the gate and depending downwardly with its opposite end freely disposed and adapted for engagement with a staple 12 which may be embedded in the ground at the inner edges of these sections. A pair of posts 13 are arranged at each side of the gate and a predetermined distance therefrom, each pair of posts being disposed in spaced relation at opposite sides of the driveway and are provided adjacent their lower edges with bearing brackets 14, within which ends of the rock shaft 15 are journaled for rotation. The shaft 15 extends transversely of the driveways and intermediate the ends is formed with a crank 16, adapted normally to extend vertically

above the surface of the ground for engagement by the wheels of the vehicle approaching the gate. Stakes 17 driven in the ground adjacent each end of the crank 16 supports the shaft, in order to prevent the distortion thereof through the weight of the vehicle when passing thereover. At each end of the shaft 15 is a laterally extending arm 18, to which one end of a coil spring 19 is attached with its opposite end secured to a bracket 20 extending from the adjacent post 13, whereby to yieldably retain the crank 16 of the shaft in an upwardly extending position. Adjacent each end of the shaft 15 is also arranged an operating lever 21, extending laterally from the shaft and normally disposed vertically when the crank 16 is disposed in a vertical position. A screw eye 22 is attached at each side of the lever 21, adjacent the lower edge thereof, the screw eye remote from the gate having one end of a flexible operating member 23 attached thereto, and extending upwardly over a pulley 24, rotatably supported in a bracket 25 attached adjacent the upper end of the post 13, the operating member then extending in a direction toward the gate and over a pulley 26 mounted in a bracket 27 at the upper outer edge of the adjacent post 5. The opposite end of the flexible member 23 is then attached to the rear frame member of the gate section at a point intermediate the top and bottom edges thereof. To the other screw eye 22 carried by the operating lever 21, disposed at the side of such lever, adjacent the gate, is attached one end of a flexible member 28, which flexible member extends upwardly over a pulley 29, also rotatably mounted in the bracket 24 at the upper end of the post 13, where the member then extends in a direction toward the gate and over a pulley wheel 30 rotatably supported in a bracket 31 attached at the upper inner edge of the adjacent post 5. The opposite end of the flexible member 28 is then attached to a lever 32 pivotally mounted along the lower edge of the gate section, intermediate the inner and outer edges thereof, said lever being adapted for pivotal movement longitudinally of the lower edge of the gate section. To the free end of the lever 32 is attached a flexible member 33, extending to the latch 11 of said gate section, and adapted upon the operation of said lever to release the latch from its engagement with the staple 12, and thus permit the upward swinging movement of the gate. Each of the flexible members 23 and 28 have a weight 34 interposed therein, between the pulley wheels mounted on the post 5, and the connection of said members with the gate whereby to maintain said members in a taut condition.

At the lower inner corner of each of the gate sections is arranged a pair of dia-

nally extending brace rods 35 to the intermediate portion of each of which it attached one end of a coil spring 36 and with the opposite ends of the springs attached to the post 5, whereby to facilitate the vertical swinging movement of the gate. Each of the springs 36 are connected with their respective posts by means of a section of chain 37, whereby to provide for the adjustment of any tension of the spring. The flexible members 23 and 28 may comprise either a chain as illustrated in the present embodiment of the invention or may be in the form of a cable or rope for forming the connection between the rock shaft and the respective portions of the gate. A guard 38 is provided for each of the flexible members disposed adjacent the operating lever 21, for the purpose of retaining said members in a longitudinally extended position adjacent the opposite sides of the lever. The upper end of the operating lever 21 is formed in the shape of a fish tail as shown at 39, with the opposite ends thereof extending transversely with respect to the flexible members so as to insure an engagement of the lever therewith upon movement of the lever in either direction.

It will be apparent from the foregoing that upon the approach of the vehicle toward either side of the gate, the wheels thereof, in riding over the crank 16 will rotate the rock shaft and cause the lever 21 to move downwardly in a direction toward the gate. The initial movement of this lever upon engagement with the flexible member 28 will operate to release the latch 11 and the subsequent continued movement of the lever will operate to raise each of the gate sections upwardly and outwardly at each side of the post 5. After the vehicle has passed through the gate and coming into contact with the crank 16 of the rock shaft at the opposite side thereof, which, it will be understood, is unaffected by the opening movement of the gate, the lever 21 associated with said last named shaft will move away from the gate, for engagement with the flexible member 23, whereby through its connection with the outer edge of the gate, will cause the same to swing upwardly and inwardly into its closed position. After the vehicle has passed over the cranks 16, the springs 19 will then serve to return the cranks to their normal upwardly disposed positions.

It is obvious that the invention is susceptible of various changes and modifications, without departing from the spirit or scope of the invention or sacrificing any of its advantages, and I accordingly claim all such forms of the device to which I am entitled.

I claim:

1. A gate of the class described comprising a gate section pivotally mounted at its

outer edge for upward swinging movement, a lever pivotally mounted on the lower edge of said gate section, means for actuating said gate section for moving the latter into 5 open and closed positions, said means comprising a rock-shaft, means for mounting said rock-shaft remotely from said gate section, an operating lever mounted on said rock shaft, spring means for normally holding 10 the operating lever in a vertical position, a pair of flexible operating members, each of said operating members having one end thereof secured to said shaft on opposite sides of said operating lever, one of said 15 flexible operating members having its other end connected to said gate section rearwardly thereof and intermediate the top and bottom edges of said gate section whereby when said shaft is moved in one direction for bringing 20 said operating lever into engagement with said one flexible operating member, said gate section will be actuated for movement from an open to a closed position, the other of said pair of flexible operating members having 25 its opposite end secured to said pivoted lever carried by said gate section, latch means carried by said gate section normally securing said section in closed position, means operatively connecting said latch means 30 with said pivoted lever whereby when said shaft is initially moved in an opposite direction, said operating lever will be brought into engagement with the other of said flexible operating members, said latch mechanism 35 will be released so that a subsequent movement of said shaft may effect an upper swinging movement of said gate section, all in the manner and for the purpose set forth.

2. A gate of the class described comprising 40 a pair of gate sections pivotally mounted at their outer edges for upward swinging movement, latch means carried by each of said gate sections for normally securing said sections in closed position, means for simultaneously moving said gate sections upon 45 their pivots to open and closed positions, said means comprising a pair of vehicle operated rock shafts remotely disposed with respect to said gate sections, operating levers 50 carried by said rock shaft, spring means for normally holding the operating levers in a vertical position, flexible operating members extending from each of said shafts, means operatively connecting said flexible operating 55 members with said latch means, the ends of said flexible operating members adjacent said shafts being disposed to one side of the operating levers of said shafts, whereby upon initial movement of said shafts in one direction, said flexible members will be actuated 60 for moving said latch means to a releasing position, whereupon subsequent movement of said shafts in the same direction will effect a swinging movement of said gate section 65 for moving said section to an open position,

additional flexible operating members leading from said shafts and having their opposite ends secured to said gate section, the end of the last mentioned flexible operating members adjacent said shafts being disposed 70 on the opposite sides of the operating levers of said shafts, whereby when said shafts are moved in an opposite direction said last mentioned flexible members will be engaged by said operating levers for actuating said last mentioned flexible operating members to effect movement of said gate section to the closed position, said members arranged in the first mentioned flexible members for normally holding said flexible members in a 75 taut condition, and spring means engageable 80 with said gate section for urging said gate section for movement to an open position upon actuation of said first mentioned flexible members.

In testimony whereof I affix my signature.
CLARENCE W. EHLERS.
